UNITED STATES PATENT OFFICE.

JOHN J. PUNKE, OF DETROIT, MICHIGAN, ASSIGNOR TO HUPP MOTOR CAR CORPORATION, OF DETROIT, MICHIGAN, A CORPORATION OF VIRGINIA.

DESIGN FOR A COMBINED RADIATOR CAP AND HOOD RIDGE STRUCTURE.

Application filed August 20, 1927. Serial No. 23,157. Term of patent 3½ years.

To all whom it may concern:

Be it known that I, JOHN J. PUNKE, a citizen of the United States of America, residing at Detroit, in the county of Wayne and State of Michigan, have invented a certain new, original, and ornamental Design for Combined Radiator Cap and Hood Ridge Structure, of which the following is a specification, reference being had therein to the accompanying drawings, forming part there-

of, in which Fig. 1 is a side elevation of a combined radiator cap and hood ridge structure showing my design; and Fig. 2 is a top plan view of the same.

I claim:

The ornamental design for a combined radiator cap and hood ridge structure, substantially as shown.

JOHN J. PUNKE.
